UNITED STATES PATENT OFFICE.

HOWARD O. MILLER, OF ROCHESTER, NEW YORK.

RECEPTACLE FOR POWDERED MATERIALS, &c.

1,208,189.

Specification of Letters Patent. Patented Dec. 12, 1916.

Application filed December 7, 1915. Serial No. 65,518.

To all whom it may concern:

Be it known that I, HOWARD O. MILLER, a citizen of the United States, residing at Rochester, in the county of Monroe and State of New York, have invented new and useful Improvements in Receptacles for Powdered Materials, &c., of which the following is a specification.

This invention relates to receptacles or holders adapted to contain powdered material, such as tooth and toilet powders.

The object of the invention is to provide a receptacle adapted to hold two or more charges separated from each other, and provided with means whereby all the charges may be simultaneously confined, and either charge may be selectively dispensed.

The invention is embodied in the improvements which I will now proceed to describe and claim.

Of the accompanying drawing forming a part of this specification: Figure 1 represents a perspective view, partly broken away, of a powder receptacle embodying my invention; Fig. 2 represents a section on line 2—2 of Fig. 1; Fig. 2^a represents a modification; Fig. 3 represents a top view of the receptacle, the valve hereinafter described being removed; Fig. 4 represents a top view of the valve; Fig. 5 represents a perspective view of a different form of receptacle embodying the invention, the closure hereinafter described being removed; Fig. 6 represents a section on line 6—6 of Fig. 5, showing a part of the closure; Fig. 7 represents a view of the inner side of the closure.

Referring to Figs. 1, 2, 3 and 4, 12 represents the body of a cylindrical receptacle preferably of sheet metal, internally subdivided by radial partitions 13 into a plurality of compartments, three being here shown. The body of the cylinder has a fixed head 15 at one end, forming the outer ends of the compartments. In said head are formed openings corresponding in number and position to the compartments, each opening constituting a dispensing outlet for one of the compartments and permitting powdered material to be discharged therefrom. As here shown, there are two circular outlets 16, through which powder may issue in relatively large streams, and a third outlet provided by a group 16^a of relatively small holes through which powder may be sifted. The said outlets are arranged in a circular

series concentric with the longitudinal center of the receptacle. 17 represents a valve formed as a disk, preferably of sheet metal, closely fitting the outer side of the head 15 and pivoted thereto by a rivet 18 located at the longitudinal center of the receptacle. The valve 17 is formed to simultaneously close the compartment outlets, and is provided with a single port 19 formed and arranged to register with either of the compartment outlets, the valve at the same time closing the other outlets, so that powder may be dispensed from either compartment. The end of the receptacle opposite the head 15 is open and constitutes a filling opening communicating with all the compartments, said opening being closed by a removable cover or closure 20.

Figs. 5, 6 and 7 illustrate another embodiment of the invention, the receptacle being a shallow circular box 120 having a fixed bottom or head 150, and internally subdivided by radial partitions 130 into a plurality of compartments. The periphery of the receptacle is provided with outlets 160, 160 and 160^a corresponding to the outlets 16, 16 and 16^a in function and in arrangement relatively to the compartments. The valve is a circular band 170 preferably of sheet metal, closely embracing and adapted to turn upon the periphery of the receptacle, the valve being provided with flanges 171 bearing on the top and bottom sides of the receptacle. The valve has a single port 190 adapted to register with either of the compartment outlets. Said outlets may be simultaneously closed by the valve, and either outlet may be exposed so that powder may be dispensed from either compartment, the others being closed. The valve may be provided with a handle 172. The closed bottom or head 150 forms portions of the walls of all the compartments, and its top is annular and has a filling opening 173 communicating with all the compartments. Said opening is closed by a removable cover or closure 200, which may be secured in place by offset lugs 201 on its inner side arranged to enter slots 202 in the annular top of the receptacle, the arrangement being such that a partial rotation of the cover, after its lugs have been dropped through said slots, causes the lugs to bear on the inner surface of the annular top and secure the cover in place.

The valve 17 may be pivotally connected with the body 12 by a marginal flange 17^a.

on the valve turned over a marginal bead 12^a on the body, as shown by Fig. 2^a.

Each of the described embodiments of the invention is a selective powder dispenser including a cylindrical body, a fixed head at one end of the body, the opposite end of the body being open, and partitions subdividing the body into a plurality of compartments the walls of which are formed by the body, head and partitions. Said compartments are open at the open end of the body, so that they may be conveniently charged. The ends of the partitions at the open end of the body are formed to collectively constitute a seat for the removable closure which closes the open end, so that said closure simultaneously closes all the compartments. The external valve having a single port is conveniently operable to close all the compartments and permit powder to be dispensed from either.

Having described my invention, I claim:
A selective powder dispenser comprising

a body, a fixed head at one end of the body, the opposite end of the body being open, and partitions subdividing the body into a plurality of compartments the walls of which are formed by the body, head and partitions, said compartments being open to receive powder at the open end of the body, a closure removably engaged with the open end of the body and bearing simultaneously on said partitions to simultaneously close the compartments, each compartment having an independent outlet, and the said outlets being in a circular series, and a valve mounted on the exterior of the dispenser and rotatable relatively thereto on an axis equidistant from the compartment outlets, said valve being adapted to simultaneously close all the outlets, and provided with a single port adapted to register singly and successively with the said outlets.

In testimony whereof I have affixed my signature.

HOWARD O. MILLER.
